Primary Examiner—Wallace R. Burke
Assistant Examiner—Monica A. Hannon**[57] CLAIM**

The ornamental design for a combined doormat and ramp, as shown and described.

DESCRIPTION

FIG. 1 is a top plan view of combined doormat and ramp showing my new design;

FIG. 2 is a bottom plan view thereof;

FIG. 3 is a rear elevational view thereof;

FIG. 4 is a front elevational view thereof;

FIG. 5 is a right side elevational view thereof; the left side elevational view appears as a mirror image of the right side elevational view;

FIG. 6 is a top perspective view thereof; and,

FIG. 7 is an enlarged cross sectional right side view thereof.

FIG. 1

FIG. 2

FIG. 3

FIG. 4

FIG. 5
